CLAIM

The ornamental design for a case for earphone, as shown and described.

DESCRIPTION

FIG. 1 is a front perspective view of the case for earphone showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an exploded view thereof.

The dash-dash broken lines throughout the drawing figures depict portions of the case for earphone that form no part of the claimed design. The wave-shaped broken line illustrate a symbolic break in the disclosure. Nothing between the lines forms part of the claimed design.
